UNITED STATES PATENT OFFICE.

THOMAS J. HAYES, OF ROSLINDALE, MASSACHUSETTS, ASSIGNOR TO ARBETTER
FELLING MACHINE COMPANY, OF BOSTON, MASSACHUSETTS, A CORPORATION
OF MAINE.

NEEDLE-BAR FOR BLINDSTITCH SEWING-MACHINES.

1,334,934.

Specification of Letters Patent. Patented Mar. 23, 1920.

Application filed February 2, 1918. Serial No. 215,020.

To all whom it may concern:

Be it known that I, THOMAS J. HAYES, a citizen of the United States, and resident of Roslindale, county of Suffolk, State of Massachusetts, have invented an Improvement in Needle-Bars for Blindstitch Sewing-Machines, of which the following description, in connection with the accompanying drawing, is a specification, like characters on the drawing representing like parts.

This invention relates to improvements in needle bar mechanisms for sewing machines and more particularly to padding or felling machines in which an oscillating needle bar carries a curved eye pointed needle having a thread groove on its convex side extending substantially from the eye to the shank of the needle.

The principal object of the invention is to provide a needle bar construction which will clamp the needle more firmly than has heretofore been accomplished and which can be made at a minimum cost.

In certain usual constructions the needle bar is provided with an enlarged head having a projecting nose to give an extended bearing for the needle bar shank which is seated in a socket extending into or through said nose and head.

The nose and head is in some instances formed of two separate pieces which are clamped together and hold the needle shank between them. In other constructions the needle bar is slotted from its outer end through the bore which forms the socket for the needle shank well into the neck of the needle bar, a screw extending through one of the bifurcated portions of the head thus formed and engaging screw threads in the other serving to draw the portions of the bifurcated head together so as to clamp the needle shank in its socket.

In thus clamping the needle bar one of the sections of the bifurcated head is likely to be deflected more than the other so that the needle may be improperly positioned in respect to the stitch forming mechanism. Furthermore the force required to be applied by the screw in thus pressing the relatively thick ends of the needle bar together is so great that oftentimes the operators are unable to clamp the needle tightly in the needle bar head.

In the preferred embodiment of the invention shown herein the bore for the needle shank extends entirely through the head and nose and the slot extends only from the outer end of the needle bar into said bore, the needle being clamped in its place by a special clamping device which is located in a socket or countersink in the side of the needle bar and engages the needle shank directly.

In the present construction the side of the needle shank which is engaged by the clamping means may be flattened so as positively to prevent any rotative movement of the needle shank about the axis of the shank, thus insuring its proper positioning in relation to the elements of the complementary stitch forming mechanism.

In my construction as in those previously described the slot extending inwardly from the outer end of the needle bar forms a passage for the thread leading to the guideway in the convexedly curved side of the needle. In the present construction a guiding device is located at the mouth of the slot or passage to prevent the thread from leaving said passage and the guideway in the needle when the slack thread is given off to permit the loop to go around the bobbin or to be manipulated by such loop forming mechanism as may be comprised in the complementary stitch forming mechanism.

Other objects and features of the invention will more fully appear from the following description and the accompanying drawings and will be pointed out in the annexed claims.

The drawings illustrate a preferred embodiment of my invention as applied to a blind stitch sewing machine in which the needle oscillates in a plane inclined to the work supporting surface of the work support or to the vertical plane of the line of feed.

In the drawings,

Figure 1 is a view of the portion of the head of the sewing machine illustrating a needle bar embodying my invention mounted to oscillate in a plane inclined to the surface of the work support, also showing the presser foot and the revolving hook with which the needle co-operates.

Fig. 2 is a detail side elevation of the needle bar embodying my invention,

Fig. 3 is a rear view of the same,

Fig. 4 is a detail longitudinal median sectional view, and,

Fig. 5 is a detail transverse sectional view showing the clamping device in elevation.

5 The needle bar which is illustrated in the accompanying drawings comprises a body portion 1 having a hub 2 which is pivotally mounted upon a stud 3 in a yoke 4 upon the lower end of a needle bar supporting arm 5
10 which may be pivoted in the upper portion of the head 6 of the machine in the manner illustrated in my prior Patent No. 1,225,628
• and which may be vibrated in any desired manner such as that disclosed in my said 15 prior patent.

The body of the needle bar is provided with an extension terminating in a boss 7 which is pivotally connected to a stud 8 upon a link 9 which may be reciprocated by 20 any suitable mechanism for the purpose of oscillating the needle, such for example as that disclosed in my prior patent aforesaid.

25 A hook bracket depending from the hub of the machine carries the usual revolving hook 11 which co-operates with a curved needle 12 carried in the head 13 of the needle bar in a manner which will herein-after be more fully disclosed and which forms the substance of my present invention. 30

In the present construction, as in certain usual forms of needle bars the head 13 of the needle bar is enlarged and has an extension or nose 14 which provides an extended bearing surface for the shank of the needle. In constructions heretofore made the head and nose of the needle bar have been made in two pieces or if made in a single piece the head and nose have been 40 bifurcated, the slot forming the bifurcation extending through both the head and nose and well into the neck portion 15 of the needle bar.

In these constructions complementary 45 grooves upon the sections of the head and nose embrace opposite sides of the needle bar shank and the shank is clamped in place by screws which draw the sections or the bifurcated end portions together.

50 In such constructions the needle bar shank exerts a wedging action against the walls of the slot as the curved needle is forced into engagement with the goods so that the parts must be clamped together 55 with great force in order to hold the needle firmly in place. Furthermore in using such constructions there is usually no abutment for the end of the needle bar shank and care is required in properly positioning the 60 needle. The present invention contemplates the provision of means for more accurately positioning the needle bar shank in the needle bar and means for retaining the same in position which will clamp the needle bar 65 shank more firmly without requiring so

great an exertion upon the part of the operator.

In the preferred mechanism illustrated in the accompanying drawings the head and nose of the needle bar are provided with 70 a bore 16 extending centrally through the nose and head to receive and fit tightly the shank 17 of the needle 12. A slot 18 extends from the outer central portion of the head into the bore 16 but does not cross said bore, this slot 18 providing a thread passage or guideway leading to the thread groove in the convexedly curved side of the needle 12. A pin or stud 19 crossing the bore 16 in the rear portion of the head 75 serves to engage the end of the needle shank and provides means for accurately positioning the needle.

In order to clamp the shank of the needle in the needle bar, the side of the needle bar 80 is provided with a recess or countersink the base of which communicates with and extends slightly beyond the side of the bore 16 so that a portion of the shank of the needle will be exposed and project above the base 85 of said recess. Any suitable clamping instrumentation may be placed in the recess to engage the shank of the needle.

In the preferred embodiment of the invention illustrated herein the clamping 90 means comprises a disk or button 20 having a flat needle engaging face 20 which extends nearly across the end face of the button. The button is provided with a central aperture having screw threaded walls adapted to 100 be engaged by the threads of a machine screw 22 which passes through the opposite section of the bifurcated end of the needle bar. The disk or button 20 has opposite to the portion 20 of its face which engages the shank of the needle, a rib 23 which projects beyond the plane of the face 21 and forms a fulcrum for the button so that when the screw 22 is set up a heavy pressure may 105 be applied directly to the shank of the 110 needle.

The disk or button 20 may be prevented from turning by a pin 24 passing through a suitable aperture in said button into a socket in the needle bar. 115

In this needle bar construction as in usual forms of needle bar constructions the slot 18 forms a passage for the thread which leads directly to the guiding groove in the curved outer surface of the needle and the 120 stud 19 which is engaged by the end of the needle shank provides a guide for the running thread which prevents it from engaging the end of the needle shank and becoming chafed thereby.

In order to insure the retention of the thread in the passage 18 and guide groove in the needle a suitable guide is provided adjacent the end of the slot 18. This guide desirably is in the form of a plate 25 hav- 130

ing a thread eye therein with a slot 27 leading to said eye to facilitate the threading of the machine. The plate 25 may be secured to the needle bar head in any suitable manner as by a screw 28 and may be prevented from lateral movement by a pin 29 extending through said plate 25 into the needle bar.

The end portion of the needle bar may be 10 cut away as at 30 so that the guide plate 25 will be spaced a sufficient distance from the needle bar to permit the ready introduction of the needle thread into the threading slot 27.

15 The guide plate 25 preferably is so positioned as to lie entirely within the arc traversed by the needle bar so as to avoid the possibility of injuring the hands of the operator, an accident which frequently 20 occurs in machines in which the guide projects beyond the end of the needle bar.

It will be observed that the needle bar mechanism disclosed herein is of an exceedingly simple construction, that the 25 strength and rigidity of the needle bar is preserved, that means are provided for insuring the proper positioning of the needle and finally a more positive clamp provided than has heretofore been used which 30 will insure the preservation of the alinement of the needle.

It will be understood that the clamping mechanism disclosed herein may be used in other types of needle bar and in other 35 relations within the spirit and scope of the following claims.

Having thus described my invention what I claim as new and desire to secure by Letters Patent is;

40 1. A needle bar having an integral head bored to receive the shank of a needle and provided with a recess located transversely of and communicating with said bore whereby a section of the needle shank will project into and extend across said recess, a clamping member in said recess fulcrumed upon the bottom wall of said recess and having a needle engaging face and means located between the fulcrum and the needle 45 engaging face for applying pressure to said clamping member.

2. A needle bar having an integral head and nose bored to receive the shank of a curved eye pointed needle having a thread 55 groove in its convex side, said head being slotted from the outer end to the bore only to provide a thread passage leading to the thread groove of the needle, one side of said head having a recess extending into said bore and a needle clamping button in 60 said recess, a screw extending through said head and engaging said button adapted to force the button against the shank of the needle and thereby clamp the same firmly 65 in place.

3. A needle bar having an integral head and nose bored to receive the shank of a curved eye-pointed needle having a thread groove in its convex side, said head being slotted from the outer end to the bore only to 70 provide a thread passage leading to the thread groove of the needle, one side of said head having a recess extending into said bore and a clamping button in said recess having a rib on its needle shank engaging face 75 diametrically opposite to the portion which engages the shank of the needle, said rib forming a fulcrum for said button and a screw extending axially into said button adapted to cause said button to clamp the 80 shank of the needle firmly in place.

4. A needle bar having an integral head and nose bored to receive the shank of a curved eye pointed needle, one side of said head having a recess extending into said 85 bore, a clamping member in said recess having a flat face to engage the shank of the needle and an offset face or rib lying in a different plane and a screw extending centrally through said clamping member 90 intermediate of said rib and the surface of the face which engages the shank of the needle.

5. A needle bar having an integral head and nose bored to receive the shank of a curved eye pointed needle, one side of said head having a recess extending into said 95 bore, a clamping member in said recess having a flat face to engage the shank of the needle and an offset face or rib lying 100 in a different plane, a screw extending centrally through said clamping member intermediate of said rib and the surface of the face which engages the shank of the needle, and a pin extending through said 105 clamping member into the head adapted to prevent rotation of said clamping member in said recess.

6. A pivoted needle bar having a head and an integral nose bored to receive the 110 shank of an eye-pointed needle having a thread groove in its convex side, said head and nose having an open slot forming a thread passage in alinement with and leading to the upper end of the thread groove 115 in said needle, clamping means to engage the shank of said needle and secure the same firmly in place in said head and nose, and a thread guiding member overlying the end of said slot and terminating within the 120 sweep of the needle bar.

7. A needle bar having an integral head and nose bored to receive and fit the shank of a needle, said head being provided with a recess located transversely of and communicating with said bore whereby a section of the needle shank will project into and extend across said recess, a clamping member in said recess, means for causing 125 said clamping member firmly to engage said 130

needle shank and means for engaging the end of said needle shank whereby the same may be quickly and accurately positioned.

8. A needle bar having an integral head and nose bored to receive the shank of a curved eye-pointed needle having a thread guide on its convex side, said head and nose being slotted from the outer end to the bore to provide a thread passage leading to the thread groove in said needle, a pin extending transversely across said slot and a por-

tion of said bore forming an abutment for the end of the needle and providing a thread guide in said slot, a recess in the side of said head extending into said bore, a clamping member in said recess and means for causing the same to engage the shank of the needle and secure the same firmly in place. ¹⁵

In testimony whereof, I have signed my name to this specification.

THOMAS J. HAYES.
